Charles Coleman ^{INVENTOR}
BY
Dela S. Haynes
ATTORNEY

UNITED STATES PATENT OFFICE.

CHARLES COLEMAN FREDERICKS, OF ST. LOUIS, MISSOURI.

NONREFILLABLE CONTAINER.

Application filed October 20, 1922. Serial No. 595,797.

To all whom it may concern:

Be it known that I, CHARLES COLEMAN FREDERICKS, a citizen of the United States, and a resident of St. Louis, Missouri, have invented an Improvement in Nonrefillable Containers, of which the following is a specification.

This invention relates to a non-refillable container, preferably a steel drum.

10 Among the several objects of the invention may be noted the provision of a simple and inexpensive container adapted to accommodate a measuring or non-measuring pump for withdrawing liquid from a container; and the provision of an effective and durable device preventing refilling of the container without mutilation of the structure. Other objects will be in part obvious and in part pointed out hereinafter.

20 The invention accordingly consists of the elements and combinations of elements, features of construction, and arrangements of parts which will be exemplified in the structure hereinafter described and the scope of 25 the application of which will be indicated in the following claims.

In the accompanying drawings, in which is shown one of various possible embodiments of the invention,

30 Fig. 1 is a plan of a preferred embodiment of the invention;

Figs. 2 and 3 are central vertical sections on the line 3—3 of Fig. 1; Fig. 3 is on an enlarged scale.

35 Similar reference characters indicate corresponding parts throughout the several views of the drawings.

Referring now more particularly to Figs. 1 and 2 of the accompanying drawings, there is illustrated at 1 a container such as a 40 steel drum having a shell 3 united to the head 4 and bottom 5 at 7 by welding or other suitable means forming per se no feature of the present invention.

45 The head 4 has a boss 9 provided with a pipe tap 11 of suitable diameter such as 2 inches. Threaded in the boss is a bushing 13 centrally tapped at 15 to receive the threaded end of a suction pipe 17 extending 50 downwardly to a point adjacent the bottom of the container. Upon the lower end of the suction pipe is threaded a foot-valve casing 18 having a base slotted at 19 and resting against the bottom 5 of the container and 55 having a steel ball 21 normally resting in a 60-degree seat 23. A pin 25 is driven

through the valve housing 18 after the ball is inserted therein and prevents excessive movement of the ball.

A measuring or non-measuring pump (not shown) may be mounted in the upper portion of the threads 15 in the bushing 13, for dispensing oil or other liquids from the container. When the pump is operated to produce a suction in the pipe 17 the ball 21 lifts, admitting liquid from the container into the suction pipe. Return movement of the liquid from the suction pipe into the container is prevented because the ball seats when suction in the pipe is relieved.

70 Removal of the pipe 17 and foot valve is prevented by the bushing 13. Removal of the bushing is prevented by the safety set-screw 29 (Fig. 3) which is screwed into place when the complementary threaded recesses 31, 33 in bushing 13 and boss 9, respectively, are brought into registry with one another when the bushing has been completely threaded into the boss. After the set-screw 29 is in place at the bottom of these recesses 31, 33, the recesses are filled with litharge or other hard filler, up to the level of the top of the bushing and boss. Thereafter paint or other suitable seal 35 is applied to the outer surface of bushing and boss (and to the rest of the head if desired) to conceal the location of the recesses 31, 33. The seal 35 shows a customer at a glance that the container has not been refilled.

75 The level of liquid in the container may be conveniently shown by a float 37 mounted at the lower end of a rod 39 that passes through a plug 41 threaded in a boss 43 in the head 4 of the container. The slight clearance between rod and plug serves as a 80 vent for the container but is too small for liquid to pass therethrough into or out of the container. Removal of the plug from the boss 43 is prevented by means similar to those above described in connection with the bushing 13 and boss 9. For brevity, this 85 means will not be described again at this point.

100 In view of the above, it is believed that the various features of this invention will be clear without further elaboration, and it will be seen that with the apparatus herein described, the several objects of the invention are achieved and other advantageous results attained.

105 As many changes could be made in carrying out the above construction without de-

parting from the scope of the invention, it is intended that all matter contained in the above description or shown in the accompanying drawings shall be interpreted as 5 illustrative and not in a limitin^o sense.

I claim:

1. A non-refillable container comprising a boss on the head, a bushing threaded therein, the upper surfaces of the head and 10 bushing being flush with one another, means preventing removal of the bushing from the boss without mutilation of the device, and a suction pipe threaded into the bushing and having at its lower end a foot valve resting 15 against the bottom of the container, the foot valve comprising a casing having a slotted base, a seat in the base, a ball normally resting against the seat, and a pin adapted to be driven through the casing 20 above the ball to limit movement of the ball; said means comprising complementary threaded recesses in bushing and boss adapted to register with one another when the bushing has been screwed into place in the 25 boss, a set-screw adapted to be screwed into the lower portion of the cooperating recesses when thus in registry, and means for sealing the exposed portion of the recesses and the flush surfaces of the head and bushing 30 to thereby prevent access to the set-screw without mutilating said sealing means.
2. A non-refillable container comprising a boss on the head, a bushing threaded therein, means preventing removal of the 35 bushing from the boss without mutilation of the device, a suction pipe threaded into the bushing and having at its lower end a foot valve resting against the bottom of the container, the foot valve comprising a casing having a slotted base, a seat in the base, a ball normally resting against the seat, and a pin adapted to be driven through the casing above the ball to limit movement of the ball; said means comprising complementary 40 threaded recesses in bushing and boss adapted to register with one another when the bushing has been screwed into place in the boss, a set-screw adapted to be screwed into the lower portion of the cooperating recesses when thus in registry, and means for sealing the exposed portion of the recesses and the flush surfaces of the head and bushing 45 to thereby prevent access to the set-screw without mutilating said sealing means.
3. A non-refillable steel drum comprising a shell, a head and bottom united thereto, a tapped boss on the head extending downwardly therefrom, a bushing threaded therein and mounted flush with the head, means preventing removal of the bushing from the 50 boss without mutilation of the device, and a suction pipe threaded into the bushing and having at its lower end a check valve, said means comprising complementary

threaded recesses in bushing and boss adapted to register with one another when 65 the bushing has been screwed into place in the boss, means adapted to be screwed into the lower portion of the cooperative recesses when thus in registry, and means for sealing the exposed portion of the recesses and preventing access to the second means without mutilating said sealing means.

4. A non-refilling steel drum comprising a shell, a head and bottom united thereto, a tapped boss on the head, a bushing threaded therein, means preventing removal of the bushing from the boss without mutilation of the device, a suction pipe threaded into the bushing and having at its lower end a check valve, a float in the container, 70 a rod extending upwardly from said float, a second boss in the head, a plug threaded therein and perforated to receive said rod, and means for preventing removal of the plug from the boss without mutilation of the device, the clearance between rod and plug serving as a vent but being too small 80 to permit passage of liquid into or out of the container.

5. A non-refillable steel drum comprising 90 a shell, a head and bottom united thereto, a tapped boss on the head, a bushing threaded therein, means preventing removal of the bushing from the boss without mutilation of the device, a suction pipe threaded 95 into the bushing and having at its lower end a check valve resting against the bottom of the container, the check valve comprising a casing having a slotted base, a seat in the base, a ball normally resting against the seat, and a pin adapted to be driven through the casing above the ball to limit movement of the ball; said means comprising complementary 100 threaded recesses in bushing and boss adapted to register with one another when the bushing has been screwed into place in the boss, a set-screw adapted to be screwed into the lower portion of the cooperating recesses when thus in registry, and means for sealing the exposed portion of the recesses and preventing access to the set-screw without mutilating said sealing means; a float in the container, a rod extending upwardly from said float, a second boss in the head, a plug threaded therein and perforated to receive said rod, and means similar to said first means for preventing removal of the plug from the boss without mutilation of the device, the clearance 110 between rod and plug serving as a vent but being too small to permit passage of liquid into or out of the container.

In testimony whereof, I have signed my name to this specification this 18th day of October, 1922.

CHARLES COLEMAN FREDERICKS.
